Primary Examiner — Derrick Holland*Assistant Examiner* — Lauren Calve(74) *Attorney, Agent, or Firm* — Leason Ellis LLP**CLAIM**

The ornamental design for a shirt and bow tie arranged in packaging, as shown and described.

DESCRIPTION

FIG. 1 is a front elevation view of a shirt and bow tie arranged in packaging showing my new design;

FIG. 2 is a bottom plan view thereof;

FIG. 3 is a top plan view thereof; and,

FIG. 4 is a rear elevation view thereof.

The broken lines shown represent unclaimed subject matter and form no part of the claimed design.
